UNITED STATES PATENT OFFICE.

HARRY J. HAON AND HARRY BOICE, OF NEWBURGH, NEW YORK, ASSIGNOR TO E. I. DU PONT DE NEMOURS & COMPANY, OF WILMINGTON, DELAWARE, A CORPORATION OF DELAWARE.

ROLLING MACHINE.

Application filed April 1, 1921. Serial No. 457,642.

This invention relates to machines for folding and rolling material, such as strip fabric, upon itself, to make a folded strip of indefinite length. The illustrated machine having found particular usefulness in the art of making strips of leather substitute into gimp or welt—gimp ordinarily comprising a strip with its edge folded over upon the body of the strip, and welt comprising 10 a similarly folded strip with a welt cord enclosed within fold—we describe our invention with more particular reference to that art, but do not confine it thereto.

Gimp and welt are used in large quantities 15 for upholstery purposes and the like, as in the upholstery of automobiles, and to meet competition must be produced rapidly and properly folded, in strips of any desired length, and at a minimum of expense. The 20 present machine provides for such production.

One object of our invention is to provide a strip-rolling machine having interchangeable devices for rolling the strip, whereby 25 the machine may be adapted to the rolling of strips of different widths.

Another object is to provide a machine for making strips into either gimp or welt as desired.

30 Another object is to provide a machine for making welt and having automatically operative means for stopping the machine should a knot or the like be present in the welt cord being fed to the machine.

To these ends, and also to improve generally upon machines and devices of the character indicated, our invention consists in the various matters hereinafter described and claimed.

40 The accompanying drawings illustrate a machine embodying our invention, but we do not confine our invention thereto. In these drawings:—

Figure 1 is a front elevation with the rollers and their bearings sectioned substantially on the line 1—1, in Fig. 2, and with certain of the parts lying forward of the rollers omitted;

Figure 2 is a side elevation looking from 50 the right in Figure 1;

Figure 3 is a simplified plan view of the principal parts for handling the materials;

Figure 4 is a conventional fragmental sectional view of the rolling flanges and a portion of gimp being rolled;

Figure 5 is similar to Figure 4 but shows a portion of double-corded welt;
Figure 6 is a top view of a folding horn;
Figure 7 is an elevational view of the delivery end of the horn shown in Figure 6, 60 and

Figure 8 is a view of a roller with a somewhat different arrangement of pressing portions and spacers than that shown in Figures 1 and 3. 65

The illustrated machine comprises, broadly, a frame 1, on which are carried the pressing means, or rolling elements, designated generally as 2, the driving means 3 for the rolling elements, the fabric strip 70 suppliers 4, the cord feeders 5, and the folding devices or horns 6. The rolling elements 2 comprise a pair of driven rollers 7 and 8. Each roller includes a rolling flange, or 75 pressing portion, 7^a or 8^a mated each with the other, and each desirably of substantially the width of its mate. These receive between them the strip of material, 80 S, and press its edge, which has been turned over by the related folding horn 6, into close contact with the body of the strip. Previously to being fed to the rollers the fabric, S, is coated with adhesive upon that side of the strip, the upper side in the drawings, down on to which the turned over edge 85 is pressed; the rollers apply the pressure required to cause the folded over edge to adhere firmly to the body of the strip, making the gimp or welt. In making gimp the edge is simply folded onto and stuck to the body, 90 see "G" Fig. 4; whereas in making welt a cord C, fed to the horn 6 from a feeder 5, is placed upon the body of the strip and the edge folded over it to include it in the fold, 95 and the edge stuck to the body, as at "W" Fig. 5. In operation, with a strip S fed to the side of the machine where the rollers are turning toward each other, the strip will be carried between the rollers and pressed, and the cord C will be drawn into 100 the machine with the strip.

According to our invention a plurality of rolling flanges, each of a different width, are provided, for each roller, and each is interchangeable with the others, on the respective 105 supporting shank, as 9 or 10, of the roller. Conveniently the flanges are portions of collars, as 11 and 12, removably carried on the shanks. In this way we provide a machine readily adaptable to the making of folded 110

strips of different widths, since collars having flanges of the width desirable for the particular strip to be made can be selected and operatively installed in the machine at 5 will. It is desirable that pressing portions, e. g. flanges, be so matched with the strip to be made that the portions will press upon a sufficient width of the turned over edge to insure good joining of the edge and the 10 body, and yet the crease, or edge of the fold, will not be subjected to pressure liable to crack the leather-substitute coating, or otherwise injure the product. Also, in the case of welt the pressing portions should be narrow 15 enough to give relief for the cords (Fig. 5). It will be seen that the present arrangement of interchangeable flanges of different widths provides for the use of just the width flange best adapted to the particular article 20 to be made.

Desirably, and as shown, each roller, as assembled, may include a plurality of the flanges, as 7^a and 7^b and 8^a and 8^b. This provides for the rolling of a plurality of 25 strips at the same time. The additional flanges, as 7^b and 8^b, may be, like 7^a and 8^a, certain of the units of the sets of interchangeable flanges. Corresponding to the flanges 7^a and 8^a, the other flanges, as 7^b 30 and 8^b, are carried by collars such as 13 and 14 respectively.

In the illustrated machine the structure conveniently provides for the changing of the collars, as 11 and 13 on the upper shank 35 9, and 12 and 14 on the lower shank 10, to thereby supply such width flanges as are desired, and is as follows:—

The collars are slipped upon the shanks as indicated and backed against the shoulders 40 9^a and 10^a on the shanks. They are spaced from each other by the spacers 15 and 16, interchangeable with spacers of other widths, and of the particular width desired to give proper clearance between the various 45 strips to be folded in the specified instance, are keyed to the shanks by keys 18 and 19, and are followed by the followers 9^b and 10^b screwed on the shanks as indicated at 20 and 21. The shanks are mounted for 50 rotation in boxes 22, 22, and 23, 23, having substantially semi-cylindrical bearing surfaces 22^a and 23^a, the one embracing the lower half of the shank 10 and the other the upper half of the shank 9. The boxes 55 are removably received in openings 24 in the frame, the flanges 22^b and 23^b of the boxes overlying the margins of the openings 24 to hold the boxes in the frame. Above the upper roller 7 the openings 24 60 are each open at one side, as at 25, the height of each opening 25 being sufficient to permit the removal of the rollers and boxes. When it is desired to remove the rollers, to permit changing the collars and spacers, the here- 65 after described pressure-applying parts, 26,

27 and so forth, are disassembled, the upper roller and its boxes lifted up and taken out through the openings 25 and the lower roller lifted up and taken out. To remove the collars and spacers from the shanks the gears 70 31 and 32 are removed, the followers 9^b and 10^b unscrewed and slipped from the shanks, and the collars and spacers slipped off as desired, the box 23 between the follower 9^b and the gear 32 being of course removed. 75 When the desired rearrangements and substitutions have been made, the rollers are remounted in the frame in an evident manner.

The upper roller is urged toward the 80 lower, to give the amount of pressure between the flanges 7^a and 8^a, etc. necessary to cause proper adherence of the fold to the body of the strip, by expanding springs, or urging means, 26, 26 resting upon the upper 85 sides of the boxes 23 and located thereon by the top, or crosswise, portions of the flanges 23^b. The tension of the springs is regulated by screws, or regulating means, 27, preferably working through an equalizing arrangement, as the bars 28 and 29 and screw 30. The teeth of the gears 31 and 32 between the rollers are of course of sufficient depth to provide the desired freedom of approach of the upper to the lower roller. 95 The operation of these pressure applying parts will be evident.

The rollers 7 and 8 are driven in a direction to carry the strips into the machine from the left (Fig. 2) side. The roller 7 100 is driven from the roller 8 through the gears 31 and 32 on the rollers 8 and 7 respectively, while the roller 8 is driven directly from the driving means 3. This means comprises the driving pulley 3 carried loose and slidable upon the shaft 33, the gear 34 fast upon the shaft 33, the gear 35 fast on the shank 10 of the lower roller 8 and in mesh with the gear 34, and the friction disc 36 fast on the shaft 33 and for driven connection with the 105 pulley. Cooperative with the driving means is mechanism for controlling the position of the pulley 3 with respect to the disc 36, to make or break the drive, and comprising devices for shifting the pulley 3 along the 110 shaft to bring its friction surface 3^a into or out of frictional driving connection with the disc.

These shifting devices according to our invention preferably include an arrangement whereby should a welt cord, feeding to the machine, have a knot in it, the drive will be broken and the rollers cease to be driven. As an adjunct to this arrangement, and in further accordance with our invention, there is preferably provided a braking means for the rollers, automatically operative with the breaking of the drive to make yet surer that the rollers shall stop sufficiently soon to avoid difficulties with 115 120 125 130

the knotted cord. Thus, a control lever 37 is fulcrumed to the frame at 38 and, by link-work 47, 50, 54, later to be described in detail, is connected with a shifting-yoke device 39, or shiftable element, resting loosely between the flanges 40^a of a drum 40 which is loose and slidable on the shaft 33 but fast to the slidable loose driving pulley 3. The lever is also connected with a brake disc 41 by additional linkwork 59, 57. The disc is loose on, and slidable relative to, the shaft 33 but is held against rotation by the swivel screws 42. It is located at the opposite side of the friction disc 36 from the pulley. When the upper, or handle, end of the lever 37 is at the left (as the parts are shown in Fig. 1) the pulley is at the right in driving contact with the disc 36 and the drive is made; and the brake disc is at the right and inactive. When the lever is moved to the right, the pulley is shifted to the left and the drive broken; and the brake disc is moved to the left into contact with the friction disc 36, and brakes. The lever is urged to the right, or non-driving and braking position, by the contracting spring 43 attached at its ends to the frame 1 and the lever; but the lever is normally held against movement by a latch 44, or movable element. This latch is hinged to the frame at 45 for upward swinging, but is prevented from downward swinging by the frame as shown. When in lowered or horizontal position, it lies in the path of movement of the lever. It is provided with apertures 46 smaller than the knots, kinks, and so forth, which it is desired shall stop the machine, and the cords being fed are passed through these apertures. Evidently, when a knot reaches the bottom of the latch, the knot will lift the latch out of the way of the lever, permitting the spring 43 to move the latter and stop the machine. It will be noted that the latch 44 with its apertures 46 for the cords not only serves as a latch (and an element of the drive-controlling means) but also serves as an element of the means for guiding and presenting the cords to the rollers. Thus, as shown in Figure 3, the member 44 is located between the members 5 and 78 (hereafter mentioned) and serves to guide and control the cords in their passage between such members.

The previously mentioned linkwork for connecting the lever 37 with the pulley-shifting yoke 39 and the brake disc 41 comprises a reach lever 47 fulcrumed on the frame 1 at 48 and pivoted to the lower end of the lever 37 at 49 and to a sliding bar 50 at 51. The bar 50 is slidably mounted at one end in the aperture 52 of a bracket 53 on the frame and has its other end pivoted to a lever 54 at 81. This latter lever is fulcrumed at 55 to a bracket 56 carried by the frame and at its upper end has the

before-mentioned pulley-shifting yoke 39. Another lever, 57, is fulcrumed to the bracket 56 at 58 and at its lower end is connected with the lever 54 by the link 59 pivoted, at 60 and 61, to the levers. At its upper end 70 the lever 57 is provided with a yoke 62 which carries the previously mentioned screws 42 between which is swivelled the brake disc 41.

Of course, the various connections are sufficiently loose to permit such departures 75 from simple straight line or arcuate movements as are called for, and the elements of the linkage are proportioned to give the desired extent of movement to the pulley and the brake disc. It will be seen that 80 the described arrangement gives, upon movement of the lever 37, the before-described shifts to the pulley and the brake disc.

The folding horns 6 are mounted in any suitable manner before the rollers 7 and 8 85 and each in alignment with the particular pair of pressure applying flanges with which it is intended to cooperate. They may be of any desired character adapted to the ends sought. In Figures 6 and 7 we have illustrated in more or less detail a horn having one side adapted to fold the strip and also to guide a cord into the fold, and having the other side adapted merely to fold. In Fig. 3 we have indicated, in cooperation with the flange 7^a (and flange 8^a), a horn designed more particularly for mere folding, and have indicated, in cooperation both with the flange 7^b (and flange 8^b) and with the cord guides 5, 5, a horn having each side arranged to fold and also to guide a cord into the fold. As will be evident, the horn for merely folding at each side may in detail have each side substantially like the merely-folding side of the horn illustrated in Figs. 6 and 7; and the horn for guiding cord at each side may at each side have a construction substantially like that of the folding-and-cord-guiding side of the horn illustrated in Figs. 6 and 7. 100 105 110

The horn shown in Figs. 6 and 7 comprises a body portion in the character of a flattened tube 63 providing a strip passage 64 extending therethrough, the body having a turned down apron 63^a at its receiving end. Along its sides, and in increasing extent from the receiving end to the discharging end, the body is folded over as indicated at 65 and 66. The upper wall of the tube is cut away at the delivery end, and substantially as indicated at *a* and *b*, to provide a tongue 67, and also to remove the under-sides of the folds 65 and 66 adjacent the tongue. A cord tube 68 is fastened, as by solder, to the upper side of the tube and has its forward portion underlying the fold 66 and has its exit 69 placed adjacent the tongue 67. A portion of the tube for a short distance back from the discharge end is desirably cut away along its side facing the 115 120 125

substantially vertical wall of the fold, as indicated at *c*. The folds 65 and 66 are of a width suitable for use in making the turn-over desired for the strip of fabric and lie 5 sufficiently close to the body proper of the horn to bring the turn-over into proper position with respect to the body of the strip of fabric, ready for passing between the pressing flanges of the machine. As will be 10 seen, the strip of fabric *S* fed in at the entrance of the horn has its edges gradually turned over, as the strip moves through the horn, and emerges with its edges folded to 15 overlie the body, the cord fed through the tube lying within the fold made by the cord-feeding side of the horn and close to the line of the fold. The horn may be mounted on the frame in any desired manner, as by the horn's cross bar 70 being clamped to the 20 frame in any convenient manner as with bolts 71 (Fig. 2).

The cords may be supplied and guided to the horn in any preferred manner, it being desirable that driven means be provided for 25 pulling the cords from the source of supply, relieving the rollers from this duty. As here illustrated (Fig. 2) each cord from any source of supply (not shown) is run through a guide tube 72 and passed once around a 30 sheave 73 anti-clockwise. The sheaves are driven from the gear 35 through the pulley 74 fast connected with the driven shaft 10, the belt 75, and the pulley 76 fast on the driving shaft 77 which carries the sheaves 35 fast thereon. From its sheave, a cord is passed through guide tubes 78 and 5 to the horn. The guides 78, one for each cord, are conveniently mounted on the forward lower portion of the frame, the left hand (Fig. 1) 40 guide lying sufficiently to the right of the lever 37 to permit the necessary extent of movement thereof. The guide 5 is carried by a support 79 placing the guide in position to deliver substantially in the horizontal 45 plane of the horn, the support having its upright portions carried on the frame in non-interfering relation to the latch 44.

The strips to be folded are carried on the previously mentioned strip suppliers or rolls 50 4, one for each strip, rotatably mounted on the bar 80 in substantial alignment each with its related horn.

In Fig. 8 we have shown a roller, as 7 or 8, supplied with various flange-carrying 55 collars and spacers and illustrating one of the many possible arrangements, and several flanges and spacers of different widths. The spacers are indicated at 15^a, 15^b, and the collars at 11^a, 11^b, 11^c. As will be understood, 60 the width of a machine between the bearings may be such as called for to accommodate rollers having the number and widths of collars and spacers desired; and, in assembling a roller, the combined widths of 65 the collars and spacers used should be sub-

stantially equal to the distance from the abutment, as 9^a to the threads, as 20.

If desired one of the rollers, as 7, may, as shown, have its shank, as 9, hollow to receive a heating means, such as an electric 70 coil (not shown).

Although we have shown a machine arranged for making a strip of gimp and a strip of welt, it will of course be understood that any other desired arrangement may be 75 resorted to to meet particular needs, as for example, should it be desired to roll a plurality of strips of gimp or a plurality of strips of welt and all requiring the same, or different, width flanges, and so forth. 80

We claim:—

1. In a machine for making folded strips, a pair of matched rollers to receive the folded strip between them and press the fold, each roller having a pressing portion upstanding therefrom to give relief to a fold at each side of the strip, and mated with and opposite the pressing portion of the other roller; each of said rollers comprising a flange of greater radial dimension than the 90 body of the roller at each side of the flange thereof to present said upstanding pressing portion with relief at each side, and also comprising devices whereby other flanges of widths different from that of said flange 95 may be substituted for such flange; and means for driving said rollers.

2. In a machine for making folded strips, a pair of mated rollers to receive the folded strip between them and press the fold, each 100 roller having a pressing portion upstanding therefrom to give relief to a fold at each side of the strip, and mated with and opposite the pressing portion of the other; each of said rollers comprising a shank carrying 105 an upstanding abutment, a flange-presenting element having a flange of greater radial dimension than the body of the roller at each side thereof to present said upstanding pressing portion with relief at each side, and removable locking means for such element comprising a collar fixable upon said shank and holding said element on said shank between the collar and said abutment whereby other flange-presenting elements 110 having flanges of different widths from that of said flange may be substituted for such flange; and means for driving said rollers.

3. In a machine for simultaneously making a pair of folded strips, a pair of matched 120 rollers to receive the folded strips between them and press the folds, each roller having a pair of pressing portions upstanding therefrom to give relief at each side of a strip, said portions of each roller being spaced 125 along the roller from each other and each portion being mated with and opposite the related pressing portion of the other roller; each of said rollers comprising a pair of flanges of greater radial dimension than the 130

body of the roller at each side thereof, to present said upstanding pressing portions with relief at each side, and also comprising a spacer for spacing the flanges along the roller, and devices whereby other spacers of widths different from that of said spacer may be substituted for such spacer; and means for driving said rollers.

4. In a machine for simultaneously making a plurality of folded strips, a pair of pressing rollers, each roller presenting a plurality of strip-pressing portions outstanding from the body of the roller to give relief at each side and each pressing portion being paired with a pressing portion of the other roller, means for individually presenting a strip to be pressed to each pair of pressing portions, and means for driving said rollers.

5. In a welt-cord-controlled mechanism for combination in a machine for making folded strips with a welt-cord in the fold, such machine presenting a pair of mated rollers to receive the folded strips between them and press the fold, means for presenting a welt-cord to the rollers and means for driving said rollers; in combination, a member for mounting before said rollers and having a welt-cord passage therein of less diameter than knots in the cord, such member being adapted to be mounted on said machine for movement by a knot, and mechanism for controlling said driving means of the machine, such mechanism including said member and means correlating said

member and said driving means for disconnection of the driving means upon movement of said member by a knot.

6. In a welt-cord-controlled mechanism for combination in a machine for making folded strips with a welt-cord in the fold, such machine presenting a pair of mated rollers to receive the folded strips between them and press the fold, means for presenting a welt-cord to the rollers and means for driving said rollers; in combination, a shiftable element for operative connection to the driving means for rendering the driving means inactive upon shifting of said element, a lever, linkwork connecting said lever and said element for shifting said element upon movement of said lever, means for moving said lever, a stop for said lever for preventing its movement and in the character of a plate normally lying in the path of a movement of said lever but swingable out of said path, said plate having a cord aperture therein located for the cord being presented passing therethrough in the direction of swing of said plate, whereby, when a knot in said cord strikes, and swings said plate out of the path of said lever, said moving means moves said lever, said linkwork operates said shiftable element, and the roller drive is broken.

In testimony whereof we affix our signatures.

HARRY J. HAON.
HARRY BOICE.
